Primary Examiner — Karen E Kearney*(74) Attorney, Agent, or Firm* — Sheridan Ross P.C.(57) **CLAIM**

The ornamental design for a display screen or a portion thereof with graphical user interface, as shown and described.

DESCRIPTION

The FIGURE is a front view of a display screen or a portion thereof with graphical user interface.

The broken line showings of the display screen are for the purpose of illustrating environmental structure and form no part of the design.

1 Claim, 1 Drawing Sheet
